UNITED STATES PATENT OFFICE.

GEORGE A. BONELLI, OF KINGMAN, ARIZONA.

DITCH-DIGGER AND GRADING MACHINE.

1,360,874.

Specification of Letters Patent. Patented Nov. 30, 1920.

Application filed October 13, 1919. Serial No. 330,466.

To all whom it may concern:

Be it known that I, GEORGE A. BONELLI, a citizen of the United States, residing at Kingman, in the county of Mohave and 5 State of Arizona, have invented new and useful Improvements in Ditch-Digger and Grading Machines, of which the following is a specification.

My object is to make a ditch digger and 10 grader, and my invention consists of the novel features herein shown, described and claimed.

Figure 1 is a perspective of a ditch digger and grader embodying the principles of my 15 invention, one operation being shown in dotted lines.

Fig. 2 is a fragmentary top plan view of the ditch digger and grader shown in Fig. 1, parts being broken away and shown in section. 20

Fig. 3 is a side elevation looking in the direction indicated by the arrow 3 in Fig. 2.

Fig. 4 is a fragmentary detail perspective of the joint indicated by the arrow 4 in 25 Fig. 3.

Fig. 5 is a fragmentary detail perspective of the joint indicated by the arrow 5 in Fig. 3.

Fig. 6 is a fragmentary detail perspective 30 of the parts indicated by the arrow 6 in Fig. 2.

Fig. 7 is a fragmentary elevation looking in the direction indicated by the arrow 7 in Fig. 3.

Fig. 8 is a fragmentary detail perspective 35 of the parts indicated by the arrow 8 in Fig. 7.

Fig. 9 is a fragmentary detail perspective 40 of the parts indicated by the arrow 9 in Fig. 2.

Fig. 10 is a fragmentary detail perspective of the parts indicated by the arrow 10 in Fig. 1.

Fig. 11 is a fragmentary detail looking in 45 the direction indicated by the arrow 11 in Fig. 1.

Fig. 12 is a view in elevation looking in the direction indicated by the arrow 12 in Fig. 11.

Fig. 13 is a fragmentary perspective of a 50 modified form of ditch digger and grader embodying the principles of my invention.

Fig. 14 is a fragmentary detail perspective 55 of the automatic clutch operating mech-

Fig. 15 is a fragmentary detail of the scraper.

The ditch digger and grader is mounted or constructed upon a motor vehicle comprising a rear axle 1, a front axle 2, a frame 3 mounted upon the axles 1 and 2, wheels 4 upon the rear axle, wheels 5 upon the front axle, and an engine 6 upon the forward end of the frame 3.

Sills 7 and 8 are mounted below the axles 65 1 and 2 inside of the wheels 4 and 5 and rigidly secured to the side bars 9 and 10 of the frame 3 by braces 11. The sills 7 and 8 extend a considerable distance back of the rear end of the frame 3 and a considerable 70 distance in front of the forward end of the frame 3, and the sills 7 and 8 are just above the ground. An extension frame 12 is constructed upon the forward ends of the sills 7 and 8 substantially on a level with the 75 frame 3.

A winding drum 13 is mounted transversely and horizontally at the forward end of the frame 12. The winding drum 13 is mounted loosely upon a shaft 14 and is controlled by a clutch construction 15. A shaft 16 is mounted in the frame 12 behind the shaft 14 and connected to the shaft 14 by spur gears 17 and 18. The shaft 19 is connected to the forward end of the engine 85 shaft 20 by a coupling 21, and a bevel pinion 22 is mounted upon the forward end of the extension shaft 19 and meshes with the bevel pinion 23 upon the shaft 16. The pinion 22 is controlled by a clutch construction 24. 90

The shaft 16 extends beyond the side of the frame 12 and has an end 25 adapted to be engaged by a suitable crank wrench for starting the engine. In starting the engine the clutch 15 is disconnected and the clutch 95 24 connected, and after the engine is started the clutches 15 and 24 may be manipulated as desired.

A brake drum 26 is fixed upon the shaft 14, a brake band 27 is connected to an abutment 28 at one end and extends around the brake drum 26, a rod 29 extends through the abutment 28 and connects to the free end of the band 27, and a hand lever 30 operates the rod 29 so as to control the winding 105 drum 13.

The lever 31 controls the clutch 24, the rod 32 controls the lever 31, and the hand lever 33 controls the rod. The scraper or shovel 34 has a back 35 fitting against the 110

forward end of the frame 12 and against a stop 36, and the scraper has a bottom 37 extending forwardly from the lower edge of the back 35 and sides 38 and 39 extending 5 upwardly from the ends of the bottom 37.

The scraper 34 is pushed against the bank 40 to excavate the bank by operating the motor vehicle forwardly.

A derrick 41 is constructed upon the rear 10 ends of the sills 7 and 8, and the details of the derrick are as follows:

A crosspiece 42 connects the rear ends of the sills 7 and 8, a vertical post 43 rests upon the center of the crosspiece and is rigidly 15 secured in place, lower braces 44 and 45 connect the intermediate portion of the post 43 to the sills 7 and 8, upper braces 46 and 47 are connected to the upper portion of the post 43 by joints 48 and 49 so that the braces 20 46 and 47 may swing to or from the sills 7 and 8, and shoes 50 and 51 are fixed upon the lower outer ends of the braces 46 and 47. Ropes or cables 52 and 53 are connected to the upper end of the post 43 and extend 25 outwardly and downwardly through openings 54 in the braces 46 and 47. Knots 55 are formed upon the ropes or cables and the openings 54 are large enough for the knots to pass through. Slots 56 extend from the 30 openings 54 and the slots 56 are large enough for the bodies of the ropes and too small for the knots, so that the braces 46 and 47 may be swung outwardly and the ropes 52 and 53 passed through the openings 54 to 35 the desired extent and then the braces swung downwardly or inwardly and the ropes will engage in the slots 56 and be drawn taut. Knotted ropes 57 and 58 are connected to the lower end of the brace 46 and engage 40 forks 59 and 60 fixed upon the side bar 7 to limit the outward swing of the brace 46. In a like manner knotted ropes 61 and 62 are attached to the lower end of the brace 47 and engage forks 63 and 64 fixed upon 45 the side bar 8 to limit the outward swing of the brace 47. A pulley 65 is mounted at the lower end of the post 43 and a pulley 66 is mounted at the upper end of the post. The parts are adjusted so that the shoes 50 50 and 51 will move easily upon the face of the ground when the motor vehicle is pushing the scraper, and so that the shoe 50 will rest upon the ground when the scraper is elevated as shown in dotted lines in Fig. 1, 55 the scraper being swung to the left, and so that when the parts are shifted to swing the scraper to the right the shoe 51 will rest upon the ground and brace the derrick.

A central crosspiece 67 is fixed upon the 60 side bars 9 and 10 and guy anchors 68 and 69 extend upwardly from the ends of the crosspiece 67. The crosspiece 67 is a channel bar with the channel upwardly and the guy anchors 68 and 69 are blocks inserted 65 downwardly into the channel and fastened.

Referring to Fig. 6, a post socket 70 is fixed at the center of the crosspiece 67 and extends upwardly and the post 71 is loosely mounted in the socket 70 so that the post may be readily removed. The post 71 extends upwardly to a considerable height. 70

The boom 72 is a long heavy timber substantially as long as the side bars 7 and 8. A fitting 73 is fixed upon the rear end of the boom 72. A second fitting 74 is hinged to the rear end of the fitting 73 and has a circular stem 75 fitting in a vertical bearing 76 secured to the post 43, so that the boom 72 may swing up and down upon the hinge pin 77 and swing laterally upon the stem 75. 80 The boom 72 normally rests in a horizontal position and as shown passes upon the left-hand side of the post 71 when it is desired to dump the scraper at the left-hand side of the machine. 85

Referring to Fig. 11, a bracket 1^a is secured to the post 71, a shaft 2^a is fixed in the bracket 1^a, a spiral spring 3^a is fixed upon the shaft 2^a at its inner end and the outer end of the spring 3^a is fixed to the drum 4^a. A pawl wheel 5^a is fixed to one end of the drum 4^a. A lever 6^a is mounted upon a pivot 7^a and has a pawl 8^a engaging the pawl wheel 5^a and a handle 9^a extending upwardly and outwardly from the post 71. 95 The guy 78 is attached to and wound upon the drum 4^a and extends upwardly over the guide roller 1^b at the upper end of the post 71, and the guy 78 is connected to the boom 72 some distance in front of the post 71. 100

If it is desired to change the arrangement and dump the scraper at the right-hand side of the machine the post 71 is removed from the socket and turned half way around, the boom 72 swung over to the right-hand side 105 and the post 71 replaced in the socket.

A guy 79 is connected to the guy anchor 68 and passes over a pulley 80 at the forward end of the boom 72 and downwardly and is connected to the central portion of the top 110 of the back 35 of the scraper.

The scraper bail comprises side bars 81 and 82 connected to the forward end of the boom 72 by a pin 83 and extending downwardly and outwardly and connected to the sides 38 and 39 of the scraper by pins 84 and 85. The pins 84 and 85 are in front of the center of the scraper, so that the load of dirt in the scraper will tend to throw the scraper backwardly and not forwardly. A stop knot 115 2^b is formed in the guy 79 to engage the pulley 80 and hold the scraper 34 from tipping backwardly.

A cable 86 is attached to the drum 13 and wound upon the drum and extends backwardly between the side bars 7 and 8, under the pulley 65, upwardly over the pulley 66 and forwardly and is attached to the hook 87 fixed in the forward end of the boom 72. When the drum 13 is operated to wind the 120 125 130

cable 86 the cable will pull upwardly upon the forward end of the boom 72 thereby raising the scraper 34 carrying the load of dirt, and as the scraper is raised the tension 5 of the guy 79 pulling upwardly on the back 35 will hold the scraper upright to carry the load, and as the scraper continues to go upwardly the tension of the guy 79 will move the forward end of the boom 72 to the left 10 until the desired height is reached, then an extra strain upon the cable 86 will upset the scraper and dump the load as shown in dotted lines in Fig. 1. Releasing the cable 86 will allow the weight of the scraper to swing 15 the boom 72 backwardly toward its normal position.

When the boom 72 goes upwardly the tension of the spring 3^a will wind the guy 78 upon the drum 4^a and the pawl 8^a will hold 20 the drum 4^a to hold the guy 78, so that when the boom 72 starts downwardly the guy 78 will be short and hold the scraper 34 some distance above the ground. A nut 3^b is formed in the guy 78 in front of the 25 roller 1^b to limit the winding up movement of the drum 4^a. When the boom 72 has been lowered until the guy 78 is tight the boom 72 will swing laterally toward the post 71 thus bringing the scraper 34 directly 30 into line and then the boom 72 will strike the handle 9^a and release the pawl 8^a from the pawl wheel 5^a and the weight of the boom will unwind the guy 78 from the drum 4^a and allow the scraper 34 to settle straight 35 down into place. Then the power will be applied to move the vehicle forwardly to push the scraper into the bank 40 to obtain a new load.

When it is desired to dump the dirt to 40 the right instead of to the left the guy 79 will be connected to the guy anchor 69 and the boom 72 will be upon the right-hand side of the post 71.

Referring to the modification shown in 45 Figs. 13, 14 and 15, the elevating frame 88 is built upon the extension frame 12. The main feature of the elevating frame 88 consists of the double track bars 89 and 90 extending upwardly from the forward end 50 of the extension frame 12 and making a quarter turn above the extension frame 12 and then going straight upwardly and outwardly at right angles to the axis of the machine. Posts 91 and 92 support the upper outer ends of the track bars 89 and 90 55 and are adapted to rest upon the ground and to be moved along the surface of the ground. At the upper ends of the track bars 89 and 90 the track bars are separated 60 to produce the single tracks 93 and 94 and 95 and 96.

The scraper 97 consists of a bottom 98, a back 99 and sides 100 and 101 rigidly secured together. The U-shaped bail 102 is 65 pivotally connected at its lower ends to the

sides 100 and 101 by pins 103 and 104. Stops 105 are secured to the sides 100 and 101 to allow the bail 102 to swing upwardly to a vertical position against the stops. The pins 103 and 104 are near the back parts of 70 the sides and the stops 105 hold the scraper from tipping forwardly. Wide wheels 106 and 107 are mounted at the lower back corners of the sides 100 and 101 to run upon the double track bars 89 and 90 and to run 75 upon the single track bars 93 and 94. Narrow wheels 108 and 109 are secured to the upper rear corners of the sides 100 and 101 in planes to run upon the double track bars 89 and 90 and to run upon the single track 80 bars 95 and 96.

The cable 110 leads from the winding drum 13 upwardly around the guide pulley 111 upon the extension frame 12 and upwardly around the guide pulley 112 and 85 downwardly around the guide post 113 and is attached to the center of the bail 102. The clutch lever 114 for operating the clutch construction 24 is mounted upon a pivot pin 115 secured to the frame and extends 90 across the frame and is connected to a lever 116. The lever 116 is mounted upon a pivot 117 and has an eye 118 in its free end, and the cable 110 passes through the eye 118. A nut 119 is formed in the cable 110 so that 95 when the drum 13 is operated to pull the scraper 97 to the top of the elevating frame 88 the nut 119 will engage the eye 118 and throw the clutch 24 out and the weight of the scraper 97 will pull the cable 110 the 100 other way and return the scraper to its normal position.

The hand lever 120 is mounted convenient to the operator and a link 121 connects the hand lever 120 to the lever 114 so that the 105 operation of the scraper may be controlled by the hand lever 120 and the nut 119 and the eye 118 will then serve as a safety device to stop the pull upon the scraper 97 when it has reached its limit of travel. 110

The vehicle will be moved forwardly to push the scraper 97 into the bank and load the scraper, then the hand lever 120 will be operated to apply the power to the drum 13 and the scraper will be lifted bodily and travel along the tracks 89 and 90 until the upper end of the elevating frame is reached, then the wheels 108 and 109 will travel upon the tracks 95 and 96 and the wheels 106 and 107 upon the tracks 93 and 94, and this 115 operation will dump the load from the scraper 97 over the back 99. The wheels 106, 107, 108 and 109 have flanges to hold the wheels upon the track bars. 120

While I have shown a simple form of 125 motor vehicle for mounting and operating a ditch digger and grader it is obvious that the ditch digger and grader may be built upon or mounted upon any of the usual forms of tractors and any of the usual forms 130

of motor vehicles such as trucks or automobiles.

Thus I have produced a ditch digger and grader comprising the combination with a motor vehicle, of a scraper adapted to be pushed forwardly by the direct action of the motor vehicle, and means whereby the power plant of the motor vehicle takes the loaded scraper from its digging position in front of the motor vehicle, carries the loaded scraper upwardly and to one side, dumps the load and returns the empty scraper to dig a new load.

Various changes may be made without departing from the spirit of my invention as claimed.

I claim:

1. A ditch digger and grader comprising a motor vehicle, a derrick mounted at the rear of the motor vehicle, a boom connected to the derrick and extending to a point in front of the motor vehicle and adapted to swing up and down and laterally, a scraper connected to the forward end of the boom and adapted to fit against the forward end of the motor vehicle and be pushed into a bank, and means for operating the boom from the motor vehicle power plant.

2. A ditch digger and grader comprising a motor vehicle having a power plant, a derrick mounted at the rear of the motor vehicle, a boom connected to the derrick and extending forwardly to a point in front of the motor vehicle and adapted to swing up and down and laterally, a scraper connected to the forward end of the boom and adapted to be pushed forwardly by the motor vehicle, a guy anchor fixed at one side of the motor vehicle, a guy connecting the guy anchor to the scraper, a winding drum operated by the plant and a cable extending from the winding drum backwardly and up over the derrick and forwardly to the forward end of the boom, a post extending upwardly from the central portion of the motor vehicle, and a guy connecting the

upper end of the post to the boom; so that when the winding drum is operated to pull the cable the boom will be raised to raise the scraper and the guys will guide the boom laterally to dump the scraper and back to its normal position.

3. A ditch digger and grader comprising a motor vehicle, a derrick mounted at the rear of the vehicle, a boom connected to the derrick and extending to a point in front of the vehicle, a scraper pivotally mounted on the forward end of the boom and adapted to be pushed forward by the forward end of the vehicle, a cable and drum for raising the boom and a guy for moving the boom laterally and dumping the scraper.

4. A ditch digger and grader comprising a motor vehicle, a derrick mounted at the rear of the vehicle, a boom connected to the derrick and extending to a point in front of the vehicle, a scraper pivotally mounted on the forward end of the boom and adapted to rest against and be pushed forward by the forward end of the vehicle, a cable and drum for raising the boom, a guy to limit the raising and lowering of the boom, and a secondary guy to move the boom laterally and dump the scraper as it raises.

5. A ditch digger and grader comprising a motor vehicle, a derrick mounted at the rear of the vehicle, a boom connected to the derrick and extending to a point in front of the vehicle, a scraper pivotally mounted between depending arms pivotally mounted on the forward end of the boom, said scraper being adapted to rest against and be pushed forward by the forward end of the vehicle, a cable and drum for raising the boom, a guy to limit the raising and lowering of the boom and a secondary guy to move the boom laterally and dump the scraper as it is raised.

In testimony whereof I have signed my name to this specification.

GEO. A. BONELLI.
